FOUR-WIRE TERMINAL TRANSMISSION CONTROL

Doren Mitchell, Martinsville, N. J., assignor to
American Telephone and Telegraph Company,
a corporation of New York

Application October 6, 1931, Serial No. 567,327

5 Claims. (Cl. 179—170)

This invention relates to two-way systems for the transmission of energy, such as telephone systems, over which are transmitted the electrical waves representing speech. More particularly, the invention relates to four-wire telephone circuits having terminal arrangements for controlling the transmission thereover. With greater particularity, the invention relates to four-wire telephone circuits having a terminal connection 10 to an extending two-wire line and equipped with voice-operated transmission control apparatus.

In the usual terminal arrangement of a four-wire circuit connected to an extending two-wire line, the "transmitting" path is adapted for 15 transmission from the two-wire line, and the "receiving" path is adapted for transmission to that line. These two paths of the four-wire circuit are connected to the two-wire line through a hybrid coil, and the impedance of the two-wire line 20 is imperfectly balanced by an artificial network. The transmitting path of the four-wire circuit is usually maintained in a normal, or non-operating, condition of disability, in order that singing 25 may be prevented; arrangements are then provided whereby voice energy in the transmitting path causes the removal of this disability and the simultaneous disabling of the receiving path.

Since the balance between the two-wire line and the artificial network is not perfect, when 30 energy travels to the two-wire line over the receiving path of the four-wire circuit, a part of this energy is usually reflected over the transmitting path as "echo"; and, since the above-mentioned balance is variable, the value of this echo energy 35 will vary. If the value of the reflected or echo energy is high enough, this energy may cause false operation of the transmission control apparatus responsive to waves in the transmitting path.

40 Since the energy in the transmitting path which represents the voice of the talker connected to the two-wire line not only clears the transmitting path but also disables the receiving path of the four-wire circuit, it becomes necessary to 45 provide means whereby the distant talker whose voice energy has passed over the system to the receiving path at the near terminal can take control of the system without interruption due to later-arriving energy traveling in the opposite direction. The means for giving such control usually takes the form of apparatus responsive to 50 energy in the receiving path which, upon operation, disables the transmission control apparatus responsive to energy in the transmitting path. 55 It may be, however, that the distant end of the

four-wire circuit is connected to a mutable link—that is, a link which is noisy or unstable and from which interfering energy may be transmitted—such as a radio link. In such a case, there is the possibility of false operation of the transmission control apparatus responsive to energy in the receiving path of the four-wire circuit, because of the noise or other interfering energy, which is usually of comparatively sustained volume or slowly varying volume in contrast with the voice 10 energy, which is of rapidly fluctuating volume.

It is important that the transmission control apparatus operated from the transmitting path shall respond to weak as well as strong voice energy—to the speech of talkers who have comparatively low ability to operate such apparatus as well as to the speech of talkers with high ability for such operation. On the other hand, the proper precautions must be taken, as indicated above, against the false operation of this apparatus by the reflection of energy in the receiving path. Furthermore, it is always important that the maximum desirable volume be delivered over the receiving path.

The applicant's invention resides in four-wire 25 circuit terminal arrangements which, in view of the various problems and requirements outlined above, give satisfactory transmission, including satisfactory positive operation of the wave-responsive apparatus and prevention of the false operation of the same.

One object of the invention is the adjustment of the sensitivity of the transmission control apparatus operated from the transmitting path of the four-wire circuit so that this apparatus will 35 be responsive to talkers with different abilities to produce, without such adjustment, the operation of this apparatus.

Another object of the invention is to control the volume in the receiving path so that, without unnecessary reduction of this volume, prevention is had of false operation of the control apparatus operated from the transmitting path, in spite of varying loss in the "echo path" (including the loss due to inadequate balance between the two-wire line and the artificial network).

Another object of the invention is to prevent the false operation of the control apparatus operated from the receiving path by incoming static 50 or other interfering energy.

Furthermore, it is the object of the invention to provide terminal arrangements which so combine the various means for accomplishing the several objects stated above that a generally satis- 55

factory condition of terminal transmission control is reached.

These and other objects and features of the invention will be clearly understood when the following description is read with reference to the accompanying drawing, which shows diagrammatically, and in part schematically, a desirable circuit arrangement embodying the invention.

10 With reference to the details of the drawing, there is disclosed one terminal of a four-wire circuit which is connected to an extending two-wire line L. The four-wire circuit includes a one-way path L₁, which may be termed the transmitting path and is adapted for transmission from the two-wire line L, and a second one-way path L₂, which may be termed the receiving path and is adapted for transmission to the two-wire line. The paths L₁ and L₂ are connected to the line L through a hybrid coil, and the impedance of the line L is imperfectly balanced by an artificial network.

20 The transmitting path L₁ is normally disabled at the point a for the purpose of the suppression of singing. Connected across the path L₁ at the point b is an amplifier-detector AD₁, which indirectly controls the operation of a relay SS designed to remove the disability from the path L₁ at point a, and a relay ES, which is 30 designed to disable the receiving path L₂ at point c. Connected across the path L₂ at the point d is an amplifier-detector AD₂, which controls the operation of a relay RS designed to disable the output circuit of the amplifier-detector AD₁. As is well understood in the art, when voice energy, for instance, travels in the transmitting path L₁, the relay SS normally operates to clear the path L₁ at point a for the transmission of the voice waves, and the relay ES 40 disables the path L₂ at point c to prevent echoes. If, however, voice energy coming from the right end of the four-wire circuit over path L₂ passes point c, it causes the operation of the relay RS and the disabling of the output circuit of amplifier-detector AD₁, and later arriving energy in the transmitting path L₁ is prevented from operating relays SS and ES.

50 Volume control in the transmitting path L₁ is effected by means of a three-electrode vacuum tube T₁, which forms a bridged impedance variable with the variations of the voltage impressed on the grid of the tube. Likewise, volume control in the receiving path L₂ is effected by means of the three-electrode vacuum tube T₂, which forms a bridged impedance variable with variation of the voltage on its grid. In addition, further control of volume in the receiving path L₂ 55 may be effected by means of the three-electrode vacuum tube T₃ which forms a bridged impedance variable as indicated above.

60 The volume regulation introduced through tubes T₁ and T₂ is preferably such that the loss introduced in the transmitting path L₁ is in accordance with the voice strength of the talker connected to line L and the loss in the receiving path L₂ is increased only when the loss in the echo path is such that the reduction of received volume is necessary to the prevention of false operation of amplifier-detector AD₁. For instance, this volume regulation may be so adjusted that there is no reduction of received volume until the condition is reached which threatens false operation of the transmission control of amplifier-detector AD₁ with a terminal

balance between the line L and the network of 20 decibels (db.).

5 The adjustment of the voltages on the grids of tubes T₁ and T₂ is effected by two potentiometers P₁ and P₂, which are preferably tied together for simultaneous operation, as is indicated in the drawing. With the specific circuit arrangement disclosed, if the talker connected to line L has a weak voice, or a voice of low ability to operate the transmission control apparatus, the arm of 10 potentiometer P₁ is turned in the clockwise direction. This operation increases the normally considerable negative biasing voltage impressed on the grid of tube T₁ from the battery B₁. Such increase of negative voltage raises the bridged 15 impedance of the tube T₁ and decreases the loss introduced in the transmitting path L₁. Since the two potentiometer arms are tied together, the operation of potentiometer P₁ in the clockwise direction is accompanied by the simultaneous 20 operation of potentiometer P₂ in the same direction. This operation of P₂ reduces the normally excessive negative bias impressed on the grid of tube T₂ by the battery B₂. If the potentiometers are operated far enough in the clockwise direction, the negative voltage on the grid of tube T₂ will be so far reduced that additional 25 loss is introduced in the path L₂.

30 The filters F₁ and F₂ interposed between potentiometer P₁ and tube T₁ and between potentiometer P₂ and tube T₂, respectively, serve to prevent clicks in the transmission paths L₁ and L₂, respectively, as the result of sudden changes in the settings of the potentiometers.

35 It may be desirable to make suitable adjustments affecting directly or indirectly the operation of the transmission control relays SS and ES when false operation of these relays is threatened with terminal balances which are lower than 20 db., for instance. For this purpose the applicant connects in the output circuit of the amplifier-detector AD₁ four polar relays S₁, S₂, S₃ and S₄; this relay chain co-operates under certain 40 conditions with a marginal relay MS.

45 Relays S₁, S₂, S₃ and S₄ have operating windings w₁, w₂, w₃ and w₄, respectively, which are directly in circuit with the output of amplifier-detector AD₁. Relays S₁, S₂ and S₃ have, in addition, auxiliary windings w_{1'}, w_{2'} and w_{3'}, respectively. Furthermore, relays S₁, S₂, S₃ and S₄ 50 may be biased by windings w_{1''}, w_{2''}, w_{3''} and w_{4''}, respectively. The turns of these biasing windings are disclosed in the drawing so as to suggest graphically the relative sensitivities of the four relays; relay S₄ is more sensitive than S₃, S₃ is more sensitive than S₂, and S₂ is more sensitive than S₁. In order that the effects of the various windings of these relays may be clearly illustrated, arrows are added to the drawing which indicate the direction of pull exerted by each winding on the associated armature.

65 The marginal relay MS has two windings W₁ and W₂. The winding W₁ is under the control of an amplifier-detector AD, connected between the hybrid coil and the balancing network. The winding W₂ is under the control of amplifier-detector AD' which is connected across the transmitting path L₁ at a point close to the hybrid coil. It will be understood that energy traveling toward the four-wire circuit in the two-wire line L divides at the hybrid coil so that in response to such energy only amplifier-detector AD' will be operated. If, however, energy comes in over the receiving path L₂ of the four-wire cir- 70 75

cuit, divides at the hybrid coil and is reflected back from the line L_1 over the transmitting path L_1 of the four-wire circuit, both of the amplifier-detectors AD and AD' will be operated.

5 In order that the proper operation of these two amplifier-detectors may be assured, it is desirable to provide for adjustment of their respective sensitivities by the operation of potentiometer P_1 . For this purpose three-electrode vacuum tubes T and T' are connected in the input circuits of amplifier-detectors AD and AD' , respectively. Negative biasing voltages are impressed on the grids of these tubes by the battery B_1 , which furnishes the biasing voltage for the tube T_1 , and the bias 10 is adjusted by the operation of the potentiometer P_1 which controls the gain in path L_1 . It should be noted that the winding W_2 of relay MS should be made of equal sensitivity with relay S_4 .

It should be understood that relay S_2 , which 20 directly controls the operation of the transmission control relays SS and ES , is designed to operate in response to energy in the path L_1 of a predetermined or greater magnitude. Therefore, when energy of a lower magnitude operates the 25 amplifier-detector AD_1 (this energy representing the voice of a weak talker), relay S_2 will not operate but relay S_4 , which is considerably more sensitive, will be operated, while relay S_1 , which is less sensitive than S_2 , also remains unoperated.

30 The comparatively weak energy in path L_1 causes the energization of winding W_2 of the marginal relay MS and the armature of this relay is pulled downward. A circuit is now completed over battery, the armature of relay MS , a resistance R_2 , the armature of relay S_4 , the armature of relay S_1 , and a condenser C_4 , and the condenser is charged. A three-electrode vacuum tube T_5 acts as a valve in the circuit including the auxiliary windings w_1' , w_2' and w_3' of relays S_1 , S_2 and S_3 , respectively. It will be understood that this circuit is normally so adjusted that any force exerted by any one of these auxiliary windings will be insufficient to cause operation by itself of the relay of which the winding forms a part. When, however, condenser C_4 is charged through resistance R_2 by the completion of the above described circuit, the normal negative voltage applied to the grid of tube T_5 is reduced or partly cancelled, and an appreciable amount of current will flow through the 50 circuit including the auxiliary windings. As is indicated in the drawing, this current in the auxiliary windings aids the current flowing in the operating windings w_1 , w_2 and w_3 or, in other words, the sensitivity of the relays S_1 , S_2 and S_3 is increased. This increase of sensitivity, of course, renders the transmission control apparatus responsive to energy in the transmitting path L_1 which is below the predetermined magnitude and enables a weak talker to clear the path

55 60 L_1 at point a and to disable the receiving path L_2 at point c through the operation of relay S_2 and the resultant operation of relays SS and ES .

In connection with the circuits just discussed, the resistance R_4 associated with condenser C_4 should be quite large in order to provide for the slow leakage of the charge on the condenser upon the termination of energy transmission in the path L_1 . It should be noted further that since relay S_1 is less sensitive than relay S_2 , the above 65 described adjustment of sensitivity will give some margin against clipping.

When energy coming in over the receiving path L_2 of the four-wire circuit is of such magnitude and the balance between the two-wire line L and the artificial network is such that false opera-

tion of relays SS and ES is threatened, it becomes necessary or desirable to introduce an auxiliary regulation of loss in the path L_2 . The loss introduced by the bridged impedance of the three-electrode vacuum tube T_2' is determined by the negative voltage impressed on the grid of that tube by a battery B_2' . The incoming energy will cause the energization of winding W_1 of the marginal relay MS . This winding W_1 is shown in the drawing as larger than the winding W_2 of the relay. The effective difference between the sensitivities of the windings causes the incoming energy to pull the armature of relay MS upward. A difference in the sensitivities, however, may not be necessary, since the energy reflected back over path L_1 , which energizes winding W_2 and tends to pull the armature downward, will be of lower value than the energy operating on the winding W_1 by an amount depending on the balance between the line L and the network. When the 20 armature of relay MS is pulled upward, a circuit is prepared through battery, the armature of relay MS , the armature of relay S_3 , the resistance R_1 , and condensers C_1 and C_1' . If the reflected energy in path L_1 is of appreciable magnitude, 25 relay S_3 will operate to complete this charging circuit for condensers C_1 and C_1' and these condensers will be charged through resistance R_1 and an inductance L . The effect of this condenser charging is to reduce or partly cancel the negative bias on the grid of the tube T_2' . This reduction of bias reduces the bridged impedance and increases the loss introduced at this point in the receiving path L_2 . Since relay S_3 is more sensitive than relay S_2 , some margin is obtained against 30 false operation of the transmission control through the operation of relay S_2 . Since relays S_2 and S_3 are acted on simultaneously by any change of voltage on the grid of tube T_5 , the difference in sensitivity between these two relays is 35 maintained constant. It will be understood, of course, that if the energy in the receiving path L_2 causes the operation of relay RS through the energization of the operating winding w controlled by amplifier-detector AD_2 , the output circuit of amplifier-detector AD_1 is disabled and no control is had in response to later arriving energy 40 in path L_1 .

It remains to describe the feature of the applicant's terminal arrangement which provides 50 for the prevention of false operation of the relay RS designed to disable the output of amplifier-detector AD_1 by noise or other interfering energy coming in over the path L_2 . For this purpose the applicant employs a proportional desensitizing circuit connected across the input of amplifier-detector AD_2 , as is indicated in the drawing, together with certain other apparatus 55 now to be discussed.

The proportional desensitizing circuit comprises a plurality of vacuum tubes including the tubes T_3 and T_4 . The principle of this circuit and the operation thereof are clearly disclosed and fully discussed in United States Patent No. 1,772,551, to Mitchell and Silent, and accordingly, a detailed description or discussion herein is unnecessary. It is sufficient to state that the desensitizing circuit distinguishes between the rapidly fluctuating voice energy and noise energy or the like which is of comparatively sustained volume. The circuit operates to prevent any appreciable effect upon the apparatus which it controls by the voice energy, but to produce an appreciable effect on such apparatus in response to the energy of comparatively sustained volume. 70 75

This effect is the variation of the plate current in the tubes T_3 and T_4 (which are connected in parallel) in accordance with and in proportion to the energy of sustained volume.

5 It will be noted that the relay RS has, in addition to its operating winding w , an opposing or biasing winding w' . This winding w' is connected in the plate circuit of the tube T_4 of the desensitizing circuit. When noise energy or the like comes in over path L_2 , a bias is gradually built up in relay RS through the energization of winding w' , and this bias is sufficient to prevent the operation of relay RS even though there is full energization of the operating winding w connected in the output circuit of amplifier-detector AD_2 . In other words, the relay RS is desensitized in accordance with the noise energy, or other energy of comparatively sustained volume, to the point which prevents the operation 10 of this relay by noise or the like and the consequent undesired disabling of the output circuit of amplifier-detector AD_1 .

Since the reduction of the sensitivity of relay RS carries with it an increase of the chance of 20 false operation of the transmission control relays SS and ES by reflected energy of sustained volume in path L_1 (as this energy may have passed point d in path L_2 without operating relay RS, and in its reflected form may operate the amplifier-detector AD_1), it is desirable to introduce auxiliary adjustment of the loss introduced in path L_2 by the tube T_2 . It will be noted that a resistance R is included in the plate circuit of tube T_3 of the desensitizing device. This resistance may be variable to give a suitable additional adjustment. As the energy of comparatively sustained volume causes the operation of the desensitizing circuit, a voltage is built up across resistance R , or the effective portion thereof, which tends to cancel the negative voltage applied to the grid of tube T_2 by the battery B_2 . This auxiliary voltage reduces the impedance of the tube T_2 and increases or tends to increase the loss introduced in path L_2 . Thus, if 30 the arms of potentiometers P_1 and P_2 are turned in a clockwise direction to adjust for a weak talker, the volume in path L_2 is lowered sooner if the noise coming in over the path L_2 is high than if such noise is comparatively low. It will be noted, 40 however, that no penalty is attached to a strong talker connected to line L by reason of this auxiliary adjustment, since for such a talker the proper setting of potentiometer P_2 (and P_1) keeps the cancelling voltage applied to the grid of tube T_2 low enough to render it ineffective against 45 the normal negative biasing voltage on the grid.

The applicant's present invention contemplates the combination or various combinations of devices or circuit arrangements each of which 50 may by itself accomplish valuable adjustment relating to transmission control. Certain of the elements going to make up such combinations are disclosed and separately claimed in one or more of the following copending applications: Serial No. 559,079 filed August 24, 1931, and Serial No. 567,326 filed October 6, 1931, in the name of the applicant, and Serial No. 560,216 filed August 29, 1931, in the names of S. B. Wright and the applicant (assigned to the assignee of 55 the present application).

While the invention has been disclosed specifically for the purpose of illustration, it is to be understood that such disclosure does not necessarily limit the scope of the invention, which 60 is determined by the appended claims.

What is claimed is:

1. In a four-wire circuit having a terminal connection to an extending two-wire line, a transmitting path adapted for transmission from the two-wire line, a receiving path adapted for transmission to said line, transmission control apparatus normally responsive to energy in said transmitting path of a predetermined or greater magnitude, adjusting means responsive to energy in said transmitting path of less than the predetermined magnitude for rendering said transmission control apparatus responsive to such lower energy, and means for preventing the operation of said adjusting means in response to reflected energy in said transmitting path, said last-stated means, however, at the same time permitting the desired operation of said adjusting means in response to original energy in said path. 10

2. In a four-wire circuit having a terminal connection to an extending two-wire line, a transmitting path adapted for transmission from the two-wire line, a receiving path adapted for transmission to said line, transmission control apparatus normally responsive to energy in said transmitting path of a predetermined or greater magnitude, adjusting means responsive to non-reflected energy in said transmitting path of less than the predetermined magnitude for rendering said transmission control means responsive to such lower energy, and means responsive to energy in said transmitting path which is a reflection of energy in said receiving path for adjusting the level of energy in said receiving path. 20

3. In a four-wire circuit having a terminal connection to an extending two-wire line, a transmitting path adapted for transmission from the two-wire line, a receiving path adapted for transmission to said line, transmission control apparatus normally responsive to energy in said transmitting path of a predetermined or greater magnitude, means responsive to energy originating in said two-wire line and traveling over said transmitting path of less than the predetermined magnitude for rendering said transmission control apparatus responsive to such lower energy, disabling means responsive to energy in said receiving path for preventing the operation of said transmission control apparatus, means responsive substantially only to energy in said receiving path of comparatively sustained volume for desensitizing said disabling means, means responsive to energy in said transmitting path which is a reflection of energy in said receiving path for adjusting the loss in said receiving path, and means responsive to energy in said receiving path of comparatively sustained volume for adjusting the loss in said path. 30

4. In a four-wire circuit having a terminal connection to an extending two-wire line, a transmitting path adapted for transmission from the two-wire line, a receiving path adapted for transmission to said line, transmission control apparatus normally responsive to energy in said transmitting path of a predetermined or greater magnitude, means responsive to non-reflected energy in said transmitting path of less than the predetermined magnitude for rendering said transmission control apparatus responsive to such lower energy, disabling means responsive to energy in said receiving path for preventing the operation of said transmission control apparatus, means for adjusting the loss in said transmitting path, means operable simultaneously therewith for adjusting the loss in said receiving path, 40

means responsive substantially only to energy in said receiving path of comparatively sustained volume for desensitizing said disabling means and effecting an auxiliary adjustment of the loss in said receiving path, and means responsive to energy in said transmitting path which is a reflection of energy in said receiving path for effecting an auxiliary adjustment of the loss in said receiving path.

10 5. In a four-wire circuit having a terminal connection to an extending two-wire line, a transmitting path adapted for transmission from said two-wire line, a receiving path adapted for transmission to said line, transmission control apparatus normally responsive to energy in said trans-

mitting path of a predetermined or greater magnitude within certain upper and lower limits but substantially above the lower limit, adjusting means responsive to energy in said transmitting path within said limits but of less than said predetermined magnitude for rendering said transmission control apparatus responsive to such lower energy, and means for preventing the operation of said adjusting means in response to reflected energy in said transmitting path, said last-stated means, however, at the same time permitting the desired operation of said adjusting means in response to original energy in said path.

DOREN MITCHELL. 15
